UNITED STATES PATENT OFFICE.

CHARLES L. MOYER, OF CHICAGO, ILLINOIS.

STAND FOR ELECTRIC FLATIRONS.

Application filed November 30, 1925. Serial No. 72,079.

My invention relates to a stand for an electric iron.

There are various objections to the electric irons now in use. In the ordinary iron having no thermostat there is danger that the iron will be left with the current on and in contact with combustible material which may result in a fire. There is also the objection that even if the iron is left setting on a stand so that there is no danger of fire, the current may be left on for a long period of time, running up the electric bill.

One of the objects of my invention is to provide an improved stand for an electric iron, in which the stand has heat controlled means for cutting off the current from the iron.

A further object of my invention is to provide an improved stand for electric irons in which the stand is provided with means whereby placing the iron on the stand will throw on a switch to cause current to flow through the heating coil of the iron and in which this switch will be held in "on" position while the iron is on the stand until the heating of the heat controlled element releases this holding means to permit the switch to move to "off" position.

A further object of my invention is to provide a stand for an electric iron in which the stand is provided with a switch for controlling the current for heating the iron, which switch is controlled in a dual manner, both by the relation of the iron with respect to the stand and by the action of the heat controlled means.

A further object of my invention is to provide a stand for an electric iron having a switch subject to the above-described dual control, in which two actuating and holding means are provided for moving and holding the switch to its "on" position, one of these holding means being actuated when the iron is placed on the stand and the other being actuated when the iron is removed from the stand and in which both of these holding means are subject to control by the heat controlled means, the holding means which are controlled by the placing of the iron on the stand, being released by the heating of the

heat controlled means and the holding means which are actuated by the removal of the iron from the stand being released by the cooling of the heat controlled means.

Further objects will appear from the description and claims.

In order to apprise those skilled in the art how to practice and construct my invention, I shall now describe an embodiment thereof in connection with the accompanying drawings in which:

Figure 1 is a top plan view of a stand or support for an electrically heated flat iron;

Fig. 2 is a side elevation of the same;

Fig. 3 is a longitudinal section taken along the center of the device;

Fig. 4 is a detail view illustrating the thermal element holding the switch closed after the flat iron has been removed from the stand;

Fig. 5 is an end view of the stand illustrating the manner of mounting the switch mechanism thereon;

Fig. 6 is a transverse sectional view taken along line 6-6 of Fig. 2;

Fig. 7 is a horizontal sectional view taken along line 7-7 of Fig. 6;

Fig. 8 is a detail view of the interior of the switch housing illustrating the arrangement of the contacts therein;

Fig. 9 is a detail view of one of the parts of the switch; and

Fig. 10 is a similar view of another part thereof.

Referring now to the drawings in detail, the stand for the electric iron shown therein comprises a base 2 of sheet metal in the shape of a shallow pan having side flanges 63, a combination switch and receptacle member (Fig. 8) mounted underneath the base or pan, means controlled by the relation of the iron with respect to the stand for controlling the switch and heat controlled means controlled by the heat of the iron when placed on a stand for controlling the iron controlling means. The base 2 has a plurality of legs 3 which may be of any desired length, but it is preferable to support the base 2 a suitable distance to permit a

convenient arrangement of the switch mechanism thereunder. Legs 3 may be hollow to permit screws 4 to pass therethrough from the top of base 2 and to thread into the 5 feet 5. The front foot 5 may be integrally formed at the lower end of a channel member 6 disposed at the front end of the stand. The sides of the channel 6 receive strips 7 extending rearwardly and supported on a 10 horizontal plate 8 carried by the members 5. Plate 8 may have upstanding lugs 8' to which the strips 7 are riveted.

The combination switch and receptacle device has receptacle contacts 27 mounted in 15 recesses 25 in the base 24, for engagement with the contact blades of the plug 26 which may be connected with any suitable source of current supply.

Wires 30 and 32 lead from this combination receptacle and switch device to the electric iron to supply current for heating the coil. The switch controls the current through this heating coil. The arrangement of this switch control is shown in Figs. 6, 7 25 and 8. As shown in Fig. 8, one of the receptacle contacts 27 is connected by means of a bus bar 28 to a wiring terminal 29, to which one of the wires 30 leading to the iron is secured. The other wire 32 leading to the 30 iron is connected to a wiring terminal 29 which is connected to one of the switch contacts 34 by means of a bus-bar 33. The other receptacle contact 27 is connected with the other switch contact 31 by means of a 35 bus bar 28. The contacts 31 and 34 of this switch are mounted on an insulating base 22 secured to one of the side plates 7 by means of screws 23 having their heads accessible from, but recessed in, the outer face of the 40 base. The movable contact 35 is pivotally connected at 36 to a block of insulation 37 connected to the side plate 7.

The movable switch blade 35 makes and breaks the electrical connection between the 45 contacts 31 and 34. This switch blade has connected thereto at 44 one end of a coil tension spring 43, the other end of this spring being connected at 42 to an extension 41 on a vertically reciprocable spring shifting member 39 which is slidably mounted in slots in the parallel vertical plates 7. A spring 40 tends to hold this spring shifting member in its upper position.

I will now describe the iron controlled means for controlling the switch. These 50 comprise a pair of arms 10 which operate through the opening 11 in the base 2, each arm having an upwardly extending tip 12 located in position to be engaged by the iron when placed on the stand. These arms 10 are secured together to move as a unit, and are pivotally mounted on a pin 9 extending between and secured to the parallel side plates 7, in which the spring shifting member 39 is slidably mounted.

The arms 10 are normally urged upwardly by means of springs 13 connected to downwardly extending projections 14 on the arms 10, and also to a bolt 15 extending rearwardly from the channel member 6. It will be observed that the ends 12 of arms 10 project a distance sufficient to be depressed into their position illustrated in Fig. 3 when the flat iron partially shown in dotted lines is placed upon base 2. To the rear of projections 14, the arms 10 are provided with apertures 18 and 19, which are adapted to receive, in loosely pivoted relation, the ears 20 provided on a pair of holding dogs 21 and 22.

This spring shifting member has secured thereto, to move therewith, a pair of foot members, which cooperate with a pair of actuating and holding dogs 21 and 22 pivotally mounted at 18 and 19, respectively, on the oscillatable arms 10. The foot members 47 are caused to move with the spring shifting member 39 by means of the laterally extending wing portions 49 of the spring shifting member, which fit in slots in the flat foot members 47. The foot members 47 lie snugly against the side plates 7. Each of the foot members is provided with toe portions 50, which cooperate directly with the pivoted dogs 21 and 22.

The dogs 21 and 22 are themselves controlled by the action of the heat controlled bar 57, by means of an oscillatable member 60 pivotally mounted on the pin 9 and pivotally connected at 61 to the heat controlled bar 57. The lower end of this oscillatable member 60 is bifurcated to straddle the spring shifting member 39 and the forks of the member 60 cooperate respectively with the dogs 21 and 22. When the heat controlled bar 57 is lengthened out, due to the 100 heat of the iron when placed on the stand, the lengthening of the bar will move the pivotal point 61 to the right, as seen in Fig. 3, and this will move the lower end of the member 60 to the left and when this movement has progressed to a certain extent, the movement of the member 60 will push the lower end of the dog 21 to the left to cause it to disengage from its cooperating toe portions 50, whereupon the spring 40 will raise the spring shifting member 39 and throw the switch to "off" position to cut off the current to the iron.

In order to tend to hold the dogs 21 and 22 in operative relation with respect to the toe portions 50, a coil tension spring 52 is provided, the ends of which are connected respectively with the dogs 21 and 22. This spring will maintain the lower ends of the dogs 21 and 22 in contact with the forks of the oscillatable member 60, so that the two dogs move in unison so that as one is being moved to inoperative position with respect to the foot members 47, the other dog will be moving into operative position with respect to the foot members. Thus,

when the heating action has elongated the bar 57, as above described and has moved the dog 21 to release the left toe portions 50, the dog 22 will have swung to the left so that 5 its lower edge will lie above the right hand toe portions 50.

With the controlling parts in this position, it will be seen that when the iron is removed from the stand and the spring 13 10 acts to raise the arms 10, the switch control parts will be moved to the position shown in Fig. 4 in which the dog 22 has pressed down on the right hand toe portions 50 and has depressed the spring shifting member to 15 again move the switch to "on" position.

As soon as the iron is removed from the stand, the heat controlled bar 57 begins to cool off and this starts a movement of the dog controlling member 60 which pushes the 20 lower end of the dog 22 to the right, as seen in Fig. 4, and if continued long enough, eventually causes the dog 22 to release its cooperating toe portions 50 to permit the 25 spring shifting member 39 to move to its upper position under the action of the spring 43 to again throw the switch off.

The construction is such that if the iron is cold and is placed on the stand, the act 30 of placing it on the stand will throw the switch on and will start the current flowing through the heating coil in the iron. As the iron heats up, it transmits heat to a heat responsive element of the stand and after a predetermined desired length of time (five 35 minutes has been found satisfactory) the heat responsive element is heated sufficiently to release the dog which is holding the switch in "on" position, whereupon a spring throws the switch to "off" position. This throwing off of the switch by the heat responsive element is in itself an indication that the iron 40 is hot enough to use. This thermostatic action would prevent current from being left on for a period longer than five minutes 45 in case the user of the iron be unexpectedly called away or for any reason forget to shut off the current.

As soon as the user considers that the iron is hot enough to use, which may be 50 before the thermostat automatically throws off the switch, the iron is removed from the stand and is used in the usual ironing operation. If the iron is removed from the stand before the thermostatic element has 55 released the switch, the switch will still be held in "on" position as explained above. The construction is such that if the iron is off the stand for a certain desired predetermined length of time (2½ minutes has been 60 found satisfactory), the cooling down of the thermostatic element will automatically release the switch to permit it to move to "off" position. This will prevent any danger of a fire and will also prevent undue waste of current 65 in case the user should forget to turn

off the current or place the iron back on the stand.

It will be noted that placing the iron on the stand operates to throw the switch on and also taking the iron off the stand operates to throw or hold the switch "on" and 70 that the heating up of the heat responsive element automatically acts to release the switch after a predetermined length of time. There is thus a dual action of the thermostatic element to release the switch and a 75 dual action of the iron controlled lever for throwing on the switch.

In the operation of this device, the operator places the iron on the stand for the first pre-heating period. After the iron has heated sufficiently to start the ironing, removal of the iron from the stand reverses 80 the relation of the thermostat to the switch and keeps the switch in an "on" position, but releasable by the cooling down of the thermostat, after a predetermined period. 85 This period can be varied from 1 to 3 minutes, which covers the time in which an article is to be ironed. Placing the iron back on the stand in between the ironing operation will throw the switch to the "on" position if it has been thrown to the "off" position by the cooling of the thermostat or if the thermostat has not cooled sufficiently to 90 throw the switch, it will still hold the switch in the "on" position, but will reverse the 95 relation of the thermostat to the switch so that the expansion of the thermal unit will, in a short period of time, release the switch and cut off the current.

In operation, if the iron gets too hot, and 100 would be apt to scorch the material being ironed, it is not necessary to turn the switch or pull the plug to cut off the current, as in the period when the iron is placed on the stand to straighten out or fold the piece 105 that is to be ironed, the iron may be placed cross-wise on the stand allowing the thermal unit which controls the switch to cool off and contract, and throw the switch off. The operator can continue to iron until the iron has cooled to a temperature at which it does not iron well. Then, by placing the iron back on the stand in a normal position, the switch is automatically thrown and the iron 110 will commence to heat.

The construction is such that when the iron is placed cross-wise on the stand and rests on the side flanges 63, the switch will not be moved to "on" position even if the bottom of the iron should come down on the 115 controlling arms as the side flanges are high enough so that the arms 10 will not be moved far enough to cause the movement of the switch to "on" position.

The construction is such that on the down- 120

ward movement of the arms 10 which takes place when the iron is placed on the stand, the dog which is released by the heating of the thermostatic element will be the one which acts to hold the switch in "on" position; and such that when the arms 10 are raised, which takes place when the iron is moved from the stand, the dog which is released by the cooling action of the thermostatic element will be the one which is holding the switch in "on" position. In other words, when the iron is on the stand, the heat released dog is holding the switch on, and when the iron is off the stand, the cold released dog is the one which is holding the switch in "on" position.

I claim:

1. The combination with the stand of an electric iron of a switch mounted thereon for controlling the heating circuit of the iron, and means for controlling said switch comprising heat controlled means and means controlled by the relation of the iron with respect to said stand, said iron controlled means comprising means for holding the switch in "on" position when the iron is placed on the stand, released by the heating of the heat controlled means, and means for holding the switch in "on" position when the iron is removed from the stand, released by the cooling of the heat controlled means.

2. The combination with the stand of an electric iron of a switch mounted thereon for controlling the heating circuit of the iron, and means for controlling said switch comprising heat controlled means and means controlled by the relation of the iron with respect to said stand, said iron controlled means comprising means for holding the switch in "on" position when the iron is placed on the stand, released by the heating of the heat controlled means, and means for holding the switch in "on" position when the iron is removed from the stand, released by the cooling of the heat controlled means, and an iron controlled member depressed when the iron is placed on the stand and raised when the iron is removed, controlling both of said holding means.

3. The combination with the stand of an electric iron of a switch mounted thereon for controlling the heating circuit of the iron, and means for controlling said switch comprising heat controlled means and means controlled by the relation of the iron with respect to said stand, said iron controlled means comprising means for holding the switch in "on" position when the iron is placed on the stand, released by the heating of the heat controlled means, and means for holding the switch in "on" position when the iron is removed from the stand, released by the cooling of the heat controlled means, and an iron controlled member depressed when the iron is placed on the stand and raised

when the iron is removed, controlling both of said holding means, each of said holding means comprising a dog pivoted on said iron controlled member.

4. The combination with the stand of an electric iron of a switch mounted thereon for controlling the heating circuit of the iron, and means for controlling said switch comprising heat controlled means and means controlled by the relation of the iron with respect to said stand, said iron controlled means comprising means for holding the switch in "on" position when the iron is placed on the stand, released by the heating of the heat controlled means, and means for holding the switch in "on" position when the iron is removed from the stand, released by the cooling of the heat controlled means, and an iron controlled member depressed when the iron is placed on the stand and raised when the iron is removed, controlling both of said holding means, each of said holding means comprising a dog pivoted on said iron controlled member, said heat controlled means comprising a member movable back and forth by the heating and cooling action, which in one position, moves one dog out of holding relation with respect to the switch and in another position moves the other dog out of holding relation with respect to the switch.

5. The combination with the stand of an electric iron of a switch mounted thereon for controlling the heating circuit of the iron, and means for controlling said switch comprising heat controlled means and means controlled by the relation of the iron with respect to said stand, said iron controlled means comprising means for holding the switch in "on" position when the iron is placed on the stand, released by the heating of the heat controlled means, and means for holding the switch in "on" position when the iron is removed from the stand, released by the cooling of the heat controlled means, and an iron controlled member depressed when the iron is placed on the stand and raised when the iron is removed, controlling both of said holding means, each of said holding means comprising a dog pivoted on said iron controlled member, said heat controlled means comprising a member movable back and forth by the heating and cooling action, which in one position, moves one dog out of holding relation with respect to the switch and in another position moves the other dog out of holding relation with respect to the switch, said switch comprising a spring shifting member engageable by said dogs and moved and held thereby to move and hold the switch in "on" position.

6. The combination with a stand for an electric iron of a thermostatically controlled switch having means whereby either the placing of the iron on the stand or the taking

of the iron off the stand holds the switch in an "on" position and whereby the act either of placing the iron on the stand or taking the iron off the stand places the thermostatic control in a position, in which after a short period of time it will throw the switch off.

7. The combination with a stand for an electric iron of a switch for controlling the heating element of the iron, automatic means whereby placing the iron on the stand will cause the switch to be moved to "on" position, heat controlled means whereby the switch will be automatically moved to "off" position if the iron is allowed to remain on the stand, and means whereby the switch will be automatically moved to "on" position when the iron is removed from the stand.

8. The combination with a stand for an electric iron of a switch for controlling the heating element of the iron, automatic means whereby removing the iron from the stand will cause the switch to be moved to "on" position, and heat controlled means whereby the switch will be automatically moved to "off" position if the iron is allowed to remain off the stand.

9. The combination with a stand for an electric iron, of means mounted therewith through which current is supplied to the iron when off the stand, automatic means whereby placing the iron on the stand will cause current to be supplied to the electric iron, and heat controlled means whereby current will be automatically cut off from the iron if the iron is allowed to remain on the stand.

10. The combination with a stand for an electric iron, of automatic means whereby removing the iron from the stand will cause current to be supplied to the iron, and heat controlled means whereby current will be automatically cut off from the iron if the iron is allowed to remain off the stand.

11. The combination with a stand for an electric iron, of automatic means whereby placing the iron on the stand will cause current to be supplied to the electric iron, heat controlled means whereby current will be automatically cut off from the iron if the iron is allowed to remain on the stand, automatic means whereby current will be again supplied to the electric iron when the iron is removed from the stand, and heat controlled means whereby current will be automatically cut off from the iron if the iron is allowed to remain off the stand.

12. The combination with a stand for an electric iron, of means mounted therewith through which current is supplied to the iron, and heat controlled means mounted with the stand whereby current will be automatically cut off from the iron if the iron is allowed to remain off the stand.

13. The combination with a stand for an

electric iron, of means mounted therewith through which current is supplied to the iron, and heat controlled means mounted with the stand whereby current will be automatically cut off from the iron if the iron is allowed to remain on the stand, said means comprising a switch, a spring tending to throw said switch to open position and a heat controlled detent which releases the switch when heat rises above a predetermined point to permit said spring to open the switch.

14. The combination with a stand for an electric iron, means mounted therewith through which current is supplied to the iron, and heat controlled means mounted with the stand whereby current will be automatically cut off from the iron if the iron is allowed to remain off the stand, said means comprising a switch, a spring tending to throw the switch to open position, and a heat controlled detent which releases the switch when the heat falls below a predetermined point, to permit said spring to open the switch.

15. The combination with a stand for an electric iron, of means mounted therewith through which current is supplied to the iron, means controlled by the operator for initiating the supply of current to the iron, and heat controlled means mounted with the stand whereby current will be automatically cut off from the iron if the iron is allowed to remain off the stand.

16. The combination with a stand for an electric iron, of means mounted therewith through which current is supplied to the iron, and heat controlled means mounted therewith for cutting off current to the iron upon a rise of temperature of the heat controlled means when the iron is on the stand, and for cutting off the current to the iron upon a fall of temperature of the heat controlled means when the iron is off the stand.

17. The combination with a stand for an electric iron, of means mounted therewith through which current is supplied to the iron, and heat controlled means mounted therewith for cutting off current to the iron upon a rise of temperature of the heat controlled means when the iron is on the stand, and for cutting off the current to the iron upon a fall of temperature of the heat controlled means when the iron is off the stand, said heat controlled means comprising a bar elongated by a rise of temperature when the iron is on the stand to cause the current to be cut off and contracted when the iron is off the stand to cause the current to be cut off.

18. The combination with a stand for an electric iron, of automatic means whereby placing the iron on the stand will cause current to be supplied to the electric iron, heat controlled means whereby current will be

automatically cut off from the iron if the iron is allowed to remain on the stand, and automatic means whereby when the iron is removed from the stand before the heat controlled means has cut off the current the current will continue to be supplied to the iron for a time, and whereby as the iron is

removed from the stand after the heat controlled means has cut off the current, current will again be supplied to the iron. 10

In witness whereof I have hereunto subscribed my name.

CHARLES L. MOYER.
